UNITED STATES PATENT OFFICE.

HENRY W. LARSSON, OF SPRINGFIELD, MASSACHUSETTS, ASSIGNOR TO LARSSON WHIP COMPANY, OF SPRINGFIELD, MASSACHUSETTS, A CORPORATION OF MASSACHUSETTS.

BUTT-LOADING FOR WHIPS.

SPECIFICATION forming part of Letters Patent No. 707,124, dated August 19, 1902.

Application filed September 5, 1901. Serial No. 74,357. (No model.)

To all whom it may concern:

Be it known that I, HENRY W. LARSSON, a citizen of the United States of America, and a resident of Springfield, in the county of 5 Hampden and State of Massachusetts, have invented certain new and useful Improvements in Butt-Loading for Whips, of which the following is a full, clear, and exact description.

10 This invention relates to the handle portion or end of whips or similar devices. The stock of the whip is usually made of an elastic non-metallic material, such as ratan, and a weight of metal is generally connected to 15 it at the butt-end.

The object of my invention is to provide an improved form of weight and means for efficiently and economically securing the weight to the whip-stock.

20 Another object is to construct the rear or butt portion of the whip so that there is a degree of flexibility thereat, which is imparted by the portion of the winding material in advance of the loading and which portion in 25 advance substantially enlarges and gives form to the whip-butt.

My invention, broadly stated, consists in securing a covering of sheet fibrous material to the stem at or near the butt-end and 30 having an annular portion thereof extending toward the end and having a metal portion surrounding the stock below this covering having the annular portion embedded in it; and my invention comprises such further details of construction and arrangement, either 35 separately or in combination, as will be more particularly described hereinafter with reference to the accompanying drawings and then pointed out in the claims.

40 In the drawings, in which the characters of reference indicate corresponding parts in the several views, Figure 1 represents the stock with one corner of the covering attached thereto in the first stage of wrapping. Fig.

45 2 is a similar view showing the stock with the covering in an advanced stage of wrapping. Fig. 3 shows the stock with the covering completely wrapped thereon. Fig. 4 is a longitudinal sectional view of the stock and cov-

ering. Fig. 5 is a longitudinal sectional view 50 of the finished whip. Fig. 6 is an elevation of the whip-stock. Fig. 7 is a section of a modification.

In the several views, 12 indicates the stock or central body portion of the whip, that is 55 generally made of some non-metallic material, such as ratan, for example.

The covering 13 is of some thin flexible sheet material, preferably textile fabric, such as cotton or canvas, and is preferably cut to 60 a triangular shape, as shown in Fig. 1. One of the acute-angled corners of the covering 13, such as the corner 14, is wrapped once around the stock 12 and then preferably pasted onto the covering, as shown in Fig. 1. Thereupon 65 paste or glue is applied to one or both sides of the covering, and it is wrapped entirely around the stock 12, forming the convolutions shown in Figs. 2 and 3. From the place of attachment of the corner 14 to the stock 12 to 70 the place where the corner 15 is secured the entire surface of the stock is in contact with the covering, which will be of a tapering contour, as shown in Figs. 3 and 4; but from the place of attachment of the corner 14 to that 75 of corner 16, where the wrapping is completed, the covering will not be in contact with the stock, but will be of a flaring or substantially funnel-shaped form 18, as best shown in Fig. 4, thus forming a tapering annular space or 80 slot 19. The whip then has a loading 17 of a readily-fusible metal—such as lead, for example—molded onto the end and lower portion of the covering. This is done in any suitable manner, so that the metal will flow onto and entirely fill the annular space 19 and will also 85 cover the outside of the portion 18, thus causing the latter portion to be embedded in it. The metal is also caused, preferably, to entirely surround and envelop the stock 12 be- 90 low the wrapping 13. The outside of the metal portion 17 is preferably made tapering, so that its upper extremity 20 will merge into the wrapped covering, as shown in Figs. 5 and 6, and this taper is continued to the end 95 of the metal portion and corresponds to the taper of the covering, so that the whole will be of a uniform conical contour.

In the modification shown in Fig. 7 the covering is the same as in the other form; but the stock 120 below the attachment of the corner 14 is made of a taper corresponding to the space 19 of the covering, and hence there will be no annular space 19 formed when the cover is wrapped on the stem 120, and when the metal portion 170 is molded onto this wrapped stock the metal will not lie between the covering and the stock, but will contact with the outside only of the covering.

In Fig. 5 is shown a wrapping or layer of some suitable elastic or flexible material 21 wound or secured to the stock 12 at the location of the upper part of the metal loading 17 in order to form a cushion for the metal loading at this place, and thus increase the flexibility of the whip.

Instead of the wrapping of the textile material the covering 13 may consist of a winding of thread or yarn that can be built up to form the funnel-shaped lower portion by the well-known methods of winding cops with overlapping ends. This wrapping of threads or yarn would appear in section substantially the same as set forth in Figs. 4, 5, and 7.

Having thus described my invention, what I claim is—

1. In a whip or kindred device, the combination of a main portion; a surrounding annular portion whose larger free end extends toward the butt and a metal portion surrounding the main portion below said annular portion and having the latter portion embedded in it.

2. In a whip or kindred device, the combination of a main portion; a surrounding annular convolute covering of textile material, whose free end extends toward the butt, and a metal portion surrounding the main portion below said annular portion and having the latter portion embedded in it.

3. In a whip or kindred device, the combination of a main portion; a substantially funnel-shaped portion whose larger free end extends toward the butt, and a metal portion surrounding the main portion below said funnel-shaped portion and having the latter portion embedded in it.

4. In a whip or kindred device, the combination of a main portion; a substantially funnel-shaped portion whose larger free end ex-

tends toward the butt and whose walls taper toward the butt-end, and a metal portion surrounding the main portion below said funnel-shaped portion and having the latter portion embedded in it. 55

5. In a whip or kindred device, the combination of a main portion; a substantially funnel-shaped convolute textile portion whose larger free end extends toward the butt, and a metal portion surrounding the main portion below said funnel-shaped portion and having the latter portion embedded in it. 60

6. In a whip or kindred device, the combination of a stock having a wrapping of fabric thereon a short distance from the butt-end that tapers upwardly, and a casing of metal molded onto the stock and incasing the butt-end and also the lower portion of the wrapping. 70

7. In a whip or kindred device, the combination of a stock; a covering that has an annular portion whose larger free end extends toward the butt and also an intermediate portion; and a metal portion surrounding the stock below said covering and having the annular portion embedded in it and also incasing said intermediate portion. 75

8. In a whip or kindred device, the combination of a stock; a convolute textile covering that has a substantially funnel-shaped portion whose larger free end extends toward the butt, and whose walls diminish in thickness from an intermediate part toward each end; and a metal portion surrounding the stock below the covering and having the funnel-shaped portion embedded in it. 80

9. In a whip or kindred device, the combination of a main portion; a substantially funnel-shaped portion whose larger free end extends toward the butt, a metal portion surrounding the main portion below said funnel-shaped portion and having the latter portion embedded in it, and a non-metallic elastic portion located between the upper part of the metal portion and the stock. 85

Signed by me at Springfield, Massachusetts, this 30th day of August, 1901.

HENRY W. LARSSON.
